ATTORNEY

UNITED STATES PATENT OFFICE.

SIDNEY HUFF, OF NEW YORK, N. Y.

ROTARY BRUSH.

1,414,781.

Specification of Letters Patent.

Patented May 2, 1922.

Application filed July 17, 1919. Serial No. 311,645.

To all whom it may concern:

Be it known that I, SIDNEY HUFF, a citizen of the United States of America, and a resident of New York, in the county and State of New York, have invented a certain new and useful Rotary Brush, of which the following is a specification, the same being a full, clear, and exact description of the invention, such as will enable others skilled in the art to which it appertains to make and use the same.

This invention relates to instruments comprising a quantity of some flexible material attached to a handle or stock adapted for cleaning or rubbing purposes, and it appertains particularly to a portable appliance designed primarily to brush the filaments or capillary covering of the head by a rotatory movement.

20 My appliance may be used for the purpose of brushing away the particles of hair resting on the shoulders of a person, whose hair has been cut by a barber, or as an apparatus for a dry shampoo. Keeping in view these 25 and other objects for which the appliance is adapted, the invention consists in the construction, arrangement and operation of parts hereinafter set forth.

In the drawings which accompany and 30 form a part of this specification and in which one example or application of the invention is illustrated, Figure 1 represents a side elevation of an apparatus constructed according to my invention; Figure 2 is a 35 side elevation, partly in section, of the brush shown in Figure 1; Figure 3 is a side elevation, partly in section, of an appliance wherein the actuating means forms a part of the same; Figures 4 and 5 are views of 40 the devices illustrated in Figures 2 and 3, including means for reducing the speed thereof; and Figures 6 and 7 are respectively front and side views of the speed reducing mechanism.

45 Like numerals of reference indicate like parts in all the views.

Referring particularly to the drawings, 3 and 6 denote preferably aligned driving shafts which constitute actuating means for 50 my portable brush 1. I provide means for attaching the said parts 3 and 1 together so as to move in unison as by the plates 2, and the whole is supported when in operation by the handles 4 preferably located on opposite

sides of the brush 1, which latter may be 55 readily removed for cleaning or removal purposes.

In the apparatus shown in Figures 1 and 2, the driving shafts 3 and 6 are operated by a motor 70 connected by wires 17 to a source 60 of power, power being transmitted from the motor to the said shaft 3 by the flexible shaft 6, preferably comprising coiled wire, or by other suitable connecting means, the operation of the motor being governed by 65 controlling means therefor as a switch 8. The respective and opposite ends of the brush shaft and of the power shaft, as the flexible shaft 6, are formed, as indicated by the dotted lines, with engaging devices having means whereby the said ends may be fastened together at will so as to cause the brush shaft to be rotated by the revolution of the said power shaft.

I provide collars 5 in order to hold the 75 handles 4 in position and from longitudinal movement, although the same, being loose on the said shaft, are free to move independently of the rotation of the latter. The shaft 3 is driven in this instance by the flexible shaft 6 and is preferably made independent of the shaft 3, the two said shafts having 80 at their adjacent ends engaging or interlocking means.

I sometimes construct my apparatus so 85 that the motor shall form a part of the portable rotary brush as in Figure 3 where the shaft 3' is driven directly by the engaging means of the shaft of the motor 70 connected by wires 17 with a source of power, and 90 having a controlling switch 18, the remaining portions of the instrument being made in the manner heretofore described.

In cases where a small motor is used, the friction occasioned by the application of the 95 instrument in practice may serve to retard any excessive rotatory movement of the brush, but in instances where a larger motor is employed I may introduce a speed reducing device between the shafts 6 and 3 as 100 shown in Figure 4. In Fig. 5 the motor 70 replaces shaft 6. A convenient device of the class described comprises a box 10 containing the following mechanism:

A worm 16 on a supplemental shaft 90 105 which interlocks with the shaft 6 engages a gear 11 having pins 12 which enter slots in the periphery of the wheel 13, the shaft of

which wheel carries a gear 14 meshing with a gear 15 which latter is mounted on a supplemental shaft 30 interlocked with the shaft 3. The two-part connecting means 5 comprising the supplemental shafts 30 and 90 are supported by bearings in the housing 10.

In the various examples of the invention, the brush 1 is mounted on the shaft 3 while 10 the handles 4 may be carried by either the shaft 3 or the motor casing. The said shaft 3, and the shaft of the motor, and also the shafts 30 and 90 of the two-part connection of the gear case attachment 10 may all have 15 engaging means at the adjacent ends thereof in order that the shafts 3 and 6 may be directly connected as shown in Figure 2; or else, if desired, the said two shafts may be engaged with the intermediate connecting 20 means comprising the motor shaft as illustrated in Figure 5; or the said shafts 3 and 6 may be engaged with the intermediate two-part connection comprising the shafts 30 and 90 of the gear case 10 as shown in Figure 4; 25 or the shaft 3 and the motor shaft may be engaged with the intermediate device com-

prising the two-part connection of the gear case 10, as illustrated in Figure 5.

I wish it to be understood that I do not desire to be limited to the particular use or 30 the exact details of construction shown and described, for obvious modifications will occur to persons skilled in the art.

What I claim as my invention is:—

In a device of the class described, a brush, 35 a brush shaft and end plates provided with screws for attaching the brush to said shaft, handles on opposite sides of the brush, and longitudinally aligned means for operating said shaft and brush, and detachable means 40 adapted to be placed intermediate said brush shaft and said operating means, whereby said brush shaft may be directly or indirectly connected to said operating means.

In testimony of the foregoing specification 45 I do hereby sign the same in the city of New York, county and State of New York this 8th day of July, 1919.

SIDNEY HUFF.
